ABSTRACT OF THE DISCLOSURE

Apparatus for cleaning the internal surfaces of boilers and the like, wherein a pump is mounted on a false door for the boiler and a manifold associated with the pump is located within the boiler. A plurality of pipes are connected between the manifold and the portions of the boiler system to be cleaned to provide circulation of the cleaning fluid through the portions of the boiler system to be cleaned during operation of the pump.

This invention is for improvements in or relating to the chemical cleaning of internal surfaces. The invention is particularly, although not exclusively, concerned with the chemical cleaning of boilers and other heat exchanger apparatus having internal surfaces which require cleaning periodically to remove deposits.

In the chemical cleaning of boilers it has hitherto been customary to provide a complicated system of external pipe lines connecting an external part and a sump tank to selected external points of the boiler system so as to ensure adequate and complete circulation of the chemical cleaning composition throughout the system. This method of chemically cleaning a boiler requires a considerable time to set up and dismantle and so prolongs the period for which the boiler must remain out of action. Normally and in order to promote circulation through all parts of the boiler system the pump is arranged to introduce the chemical cleaning fluid into the top or bottom of the boiler or other units to be cleaned, the chemical cleaning fluid being returned to the sump tank through a number of connections on the bottom rear wall box, side wall box, water pocket or muddrum and superheater on top of the boiler. External lines are a nuisance in boiler houses and furthermore there is a danger of the cleaning acid or other cleaning fluid leaking at points along the system and doing damage to either the plant itself or to the operatives and their clothing.

An object of the present invention is to provide a system in which chemical cleaning of internal heating surfaces, for example boilers, is effected without the heretofore objectionable arrangement of external lines, connection points to the boiler system, and sump tanks.

According to the present invention there is provided a method of chemically cleaning systems or apparatus having internal surfaces (e.g., the internal surfaces of boiler systems) which comprises introducing into the system or apparatus, at least partially, means for circulating the chemical cleaning fluid, closing the system or apparatus and then circulating for the required time the chemical cleaning fluid in a closed circuit and subsequently removing the chemical cleaning fluid and the means for circulating it.

In one convenient manner of carrying out the method according to the invention a pump for circulating the chemical cleaning fluid is introduced into a drum (e.g., a steam drum) at the upper part of a boiler or similar system so that the pump is wholly submerged or enclosed in the drum and serves to circulate the cleaning fluid as a

2

closed circuit through the boiler tubes and back into the drum. Circulation can be controlled or directed by coupling the outlet of the pump internally, by flexible pipes, to appropriate parts of the boiler system. In one convenient arrangement the pump is mounted on the inner face of a false door for the steam drum, the normal door having been removed. In one preferred arrangement the pump is driven by a pneumatic motor. In this case airline connections are provided on the false door or directly on the motor for connection to compressed airlines from any convenient source which may be either an existing compressed air supply or for example a compressed air pump or bottle.

In an alternative arrangement the pump and its driving motor are arranged externally of the drum or the like and the false door carries a manifold or the like connected to the pump and from which the chemical cleaning fluid can be distributed to appropriate parts of the boiler or other system (e.g., by flexible pipes) when the false door is in position and the pump in operation.

Conveniently the chemical cleaning liquid is introduced into the system so as substantially wholly to fill the system or those parts of the system to be treated, the arrangement being such that a closed circuit is established over which the pump when in operation can circulate the cleaning fluid. To ensure good distribution of the chemical cleaning fluid the outlet side of the pump or if convenient the whole of the pump may be situated in or lead into a manifold the manifold extending substantially along the length of, or along any desired length of the drum or header tank of the system as the case may be. Thus, the cleaning fluid from the pump is delivered along the length of the manifold and conveniently spaced outlets along the manifold permit the fluid to leave it and enter the boiler or other system at appropriate points.

If desired one or more of the outlet holes in the manifold may be connected by, for example, flexible piping, to any required part of the boiler system so that the circulation of cleaning fluid is confined to those particular parts of the system requiring treatment.

In cases where the pump is situated outside the boiler or other system to be cleaned it may be mounted on the outside of a false door for a drum or header of the system. Alternatively the false door may be provided with coupling means for two or more pipes (e.g., a feed and return pipe) or other conduits which connect the pump to the interior of the boiler system for the circulation of the cleaning fluid through the appropriate parts thereof.

In a still further arrangement where a pump is situated outside the boiler system, the door of the drum or some other convenient component of the system is provided permanently with closable portways. With this arrangement all that is necessary for carrying out the cleaning operation is for the external pump to be connected by flexible pipes to said portways, the system filled with cleaning fluid, and the pump operated so as to circulate said fluid through the boiler system whilst the pump is in operation.

Two particular embodiments of the invention will now be described by way of example as applied to a boiler system and with reference to the accompanying diagrammatic drawings.

On the drawings:

FIGURE 1 is a perspective view of one arrangement.

FIGURE 2 is a perspective view of the second arrangement and

FIGURES 3, 4 and 5 are detailed views of a false door for use in the arrangement shown in FIGURE 2.

Referring first to the embodiment of the invention shown in FIGURE 1 the boiler system comprises the

steam drum 10, a lower water drum 11, side wall mud box 12, downcomers 13, side water wall tubes 14 and rear water wall tubes 15.

It will be appreciated that in practice the boiler system may be much more complex than is shown in FIGURE 1, which has been simplified for the purpose of illustrating the invention.

For the purpose of the invention the steam drum 10, is adapted to be provided temporarily (e.g., when cleaning is to be effected) with a false door 16. This false door carries a pump 17 in which is incorporated a pressure fluid (e.g., pneumatic) driving motor. Intake and exhaust pipes 18 and 19 respectively for the operation of the motor of the pump 17 are connected, by way of unions 20 and 21 on the false door 16, to the motor. The pipes 18 and 19 are provided with control valves 18a and 19a.

The fluid circulating pump 17 includes a discharge manifold from which can be led a plurality of flexible tubes 22 adapted to be inserted in the downcomers 13.

When it is required to effect cleaning of the boiler system internally the normal door on the steam drum is removed and replaced by the false door 16 so that the pump 17 is introduced into the steam drum. The tubes 22 having been introduced into the appropriate downcomers the pump is set in operation so as to circulate 25 the cleaning fluid, a supply of which has been introduced into the steam drum, into the boiler system by way of the downcomers 13 and back to the drum by way of the side and rear wall tubes 14 and 15.

When cleaning of the boiler system has been completed 30 the false door 16 is removed and replaced by the normal door, the cleaning fluid having been pumped or otherwise extracted from the system.

The embodiment of the invention shown in FIGURES 2, 3, 4 and 5 is similar in some respects to that already 35 described with reference to FIGURE 1 and where applicable like reference numerals have been used to designate like parts. In the arrangement shown in FIGURE 2, however, the pump 17 is located outside the steam drum 10 and is connected by feed and return pipes 23 and 24 respectively to a fluid distributor box mounted on the inside of the false door 16.

The fluid distributor box is shown in detail in FIGURES 3, 4 and 5 and comprises connections 25 and 26 respectively for the feed and return pipes 23 and 24. The connection 25 communicates with the distributor box proper 27 which has a plurality (in this case six) of outlets 28. The outlets 28 are adapted for connection to the flexible tubes 22 by which the cleaning fluid is introduced into the downcomers 13.

The exhaust connection 26 is adapted for connection to a pipe 29 which extends along the lower part of the steam drum and serves to return to the pump the cleaning fluid after the latter has been circulated back to the steam drum through the side wall and the rear wall tubes 14 and 15.

Here again all that is necessary to effect cleaning of the boiler system is temporarily to replace the normal door of the steam drum 10 with the false door 16 and

set the pump in operation for as long as may be necessary to effect proper cleaning of the system. The cleaning fluid is drawn from the steam drum, into which it is introduced for the cleaning operation, circulated through the system, returned to the steam drum and re-circulated as long as the pump is in operation.

Various arrangements may be provided for securing the false door in position but one convenient arrangement comprises an over centre cam or like clamping arrangement.

We claim:

1. Apparatus for chemically cleaning the internal surfaces of water tube boilers and the like by artificially creating a normal fluid circulation therein, said boilers having an upper drum portion having a first opening therein, a lower drum portion having a second access opening therein for the removal of sludge and a plurality of downcomers and risers coupling said lower and upper drum portions, said cleaning apparatus comprising:

a false door adapted to be applied to said first opening in said upper drum portion of the boiler to be cleaned;

a pump coupled to said false door;

a manifold associated with said pump and adapted to be located within said boiler;

a first plurality of flexible pipes, one end of each of said first plurality of pipes being coupled to the output port of said pump via said manifold, the other ends of said first plurality of pipes being inserted into said downcomers of the boiler system to produce pressure and a high velocity fluid stream in the downcomers; and

a second plurality of flexible pipes, one end of each of said second plurality of pipes being coupled to the inlet port of said pump via said manifold, the other ends of said second plurality of pipes being coupled to said risers for returning said cleaning fluid to said pump.

2. Apparatus as claimed in claim 1, wherein said manifold is mounted to the inner face of said false door.

3. Apparatus as claimed in claim 1, wherein said pump is mounted on the inner face of said false door.

4. Apparatus as claimed in claim 1, wherein said pump is provided with a pressure fluid driving motor.
